Patented Nov. 9, 1915.

*Inventor,
Andrew Thompson, by
G. C. Kennedy,
Attorney.*

UNITED STATES PATENT OFFICE.

ANDREW THOMPSON, OF WATERLOO, IOWA, ASSIGNOR OF ONE-HALF TO JOHN E. BATES, OF WATERLOO, IOWA.

DESIGN FOR A SPRAYING DEVICE FOR LAWN-HOSE.

48,137.

Specification for Design.

Patented Nov. 9, 1915.

Application filed June 17, 1915. Serial No. 34,751. Term of patent 7 years.

To all whom it may concern:

Be it known that I, ANDREW THOMPSON, a citizen of the United States, residing at Waterloo, in the county of Blackhawk and State of Iowa, have invented a new, original, and ornamental Design for a Spraying Device for Lawn-Hose, of which the following is a specification, reference being had to the accompanying drawing, forming part thereof.

The figure is an elevation of a sprayer head for lawn hose, showing my new design.

I claim:

The ornamental design for a spraying device for lawn hose, as shown.

Waterloo, Iowa, May 31, 1915.

ANDREW THOMPSON.
